(57) **CLAIM**

The ornamental design for an eyeglass frame, as shown and described.

DESCRIPTION

FIG. 1 is a perspective view of an eyeglass frame showing my new design;

FIG. 2 is a front side elevational view thereof;

FIG. 3 is a rear side elevational view thereof;

FIG. 4 is a left side elevational view thereof, the right elevational view being a mirror image of FIG. 4;

FIG. 5 is a top plan view thereof; and

FIG. 6 is a bottom plan view thereof; and,

FIG. 7 is a front perspective view of the eyeglass frame of the present invention, the broken line showing of a lens is for illustrative purposes only and forms no part of the claimed design.
